APPARATUS FOR PACKING UNITS OF MATERIAL

Herman L. Diehl, Ambler, Pa.

Application March 29, 1940, Serial No. 326,600

9 Claims. (Cl. 226—16)

The object of this invention is to devise a novel apparatus for assembling and packing articles in containers, and while not limited to such use, is particularly adapted for automatically assembling and packing shredded wheat biscuits in the conventional cartons in which they are sold.

A further object of the invention is to devise a novel automatic machine which will assemble super-imposed layers of articles with separators between the layers in a basket, then move the assembled articles and separators as a unit upwardly into an inverted carton, and close the open flaps of the carton.

With the above and other objects in view, as will hereinafter clearly appear, my invention comprehends a novel apparatus for packing units of material.

It further comprehends a novel packing machine having novel mechanism for removing the articles from a conveyor as they are fed from the oven; novel mechanism for assembling them in superimposed layers with separators between adjoining layers in a basket; novel mechanism for removing them as a unit from a basket into an inverted container, and novel timing means for occasioning the cyclical operation of said mechanism.

It further comprehends other novel features of construction and advantage which will herein-after be set forth in detail.

For the purpose of illustrating the invention, I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figures 1 and 2 are top plan views of a machine embodying my invention, with certain of the parts omitted for the sake of clearness of illustration.

Figure 3 is an end elevation, partly in section, viewed from the left hand end of the machine.

Figure 4 is a sectional view taken substantially on line 4—4 of Figure 2.

Figure 5 is a plan view of the driving mechanism.

Figure 6 is a diagrammatic view of timing and control mechanism.

Figure 7 is a top plan view, partly in section, of a basket on an enlarged scale.

Figure 8 is a side elevation on an enlarged scale and partly in section of a transfer box.

Figure 9 is a section on line 9—9 of Figure 8.

Figure 10 is an end view in section of a conveyor.

Figure 11 is a sectional elevation on an enlarged scale of a carton container.

Similar numerals indicate corresponding parts.

Referring to the drawings:

1 designates the frame of the machine, having any desired construction and arrangement.

The machine is driven by a motor 2, see Figures 3 and 5, the shaft of which has a sprocket wheel 3 to receive a sprocket chain 4 which passes around a sprocket wheel 5 fixed to a main driving shaft 6 suitably journaled in the frame of the machine.

A sprocket wheel 7 fixed to the shaft 6 has a sprocket chain 8 which passes around a sprocket wheel 9 fixed to a shaft 10 suitably journaled in the machine frame.

The units of material, such as for example shredded wheat biscuits, are fed from a conventional oven, not shown, by a conveyor 11 driven by drums 12, see Figure 3.

The main driving shaft 6 has a sprocket wheel 13 provided with a sprocket chain 14 which passes around a sprocket wheel 15 fixed to a shaft 16, journaled in the machine frame. The shaft 16 has one end of driving arms 17 fixed to it and the other ends of such arms are pivotally connected with links 18, the forward ends of which are pivotally connected with a rod 20 which carries a pusher 21 having a flange 22 extending downwardly into proximity to the article conveyor 11. The ends of the rod travel in endless tracks 23 in plates 24 having lower and upper stretches 25 and 26 connected at their front ends by an inclined stretch 27. A pivoted latch 28 causes the rod to travel rearwardly in the upper stretches so that the flange 22 of the pusher will be raised above the articles on the conveyor 11 while the pusher is making its rearward stroke. The reciprocatory movements of the pusher moves a row of articles on the conveyor 11 over the table 29 and into a basket 30, in which the articles are assembled in rows one above the other with separators 31 between superimposed rows.

50 The article receiving baskets and their adjuncts

Referring now more particularly to Figures 1, 2, 3 and 7, each basket 30 has a closed bottom 32, vertically spaced side angles 33, vertically spaced separator strips 34 carried by the back wall 35

and spaced stops 36 between which ejectors 37 are adapted to pass to eject assembled articles from the basket as will be hereinafter explained.

The ejectors are connected with a bar 38 which passes through a grooved guide block 39 fixed to the rear wall of a basket.

In order to permit the raising and lowering of the baskets 30 during the operations of inserting the separators and the articles, a double link conveyor 40 is connected with shoes 41 mounted in the guide blocks 39 and provided with rollers 42 which at times travel on the tracks 43. The link conveyor passes around link wheels 44 mounted on rods 45 forming a part of the machine frame, see Figure 3.

In order to provide a take-up for any stretch of the conveyor links, alternate links have a turn buckle arrangement, the ends of a link being connected by a rod having a right and a left hand thread as at 46, see Figure 11.

The downward movement of a basket 30 is limited by a collar 47 which engages a seat 48 on a shoe 41, see Figure 7.

Some of the links of the conveyor have blocks 49 with inclined faces 50 at their forward end. A hydraulic cylinder 51 has its plunger provided at its forward end with a pivoted arm 52 which moves in the path of the blocks 49 and is provided with a spring 53 to return it to its normal position as it is moved by the inclined face 50 of a block travelling by it. It will thus be clear that as the hydraulic cylinder 51 is actuated the link conveyor and the baskets 30 are intermittently advanced step by step.

The ejectors 37 are connected with the guide block 39 by springs 54 which return the ejectors to their initial position within the basket.

Separators and their operating means

The first step in the operation of filling the baskets is the assembling therein of spaced separators. The separators 31, see Figure 3, are stacked in skeleton frames 55 each being made of four upright angles and supported on the floor. A plate 56 is connected to the plunger of a hydraulic cylinder 57 which provides a very slow upward travel of the stack of separators. The plate 56 is guided on four posts forming a part of the machine frame. A suction cup 58 rests on the top separator of a stack and is connected with the plunger of a suction cylinder 59 mounted on a roller carriage 60 mounted in channels 61 supported on posts forming a part of the machine frame. One of the suction cylinders 59 is connected with the plunger of a hydraulic cylinder 62, the operation of which is timed to move the separators 31 at the proper time into the baskets so that they will be superimposed in spaced relationship, three baskets at a time, as illustrated, being supplied with separators.

The shaft 10, see Figure 3, has cams 64 cooperating with rollers 65 on rods 66 guided in guide brackets 67 and having their upper ends adapted to engage the guide blocks 39 to effect at the proper times the positioning of baskets to receive separators.

The next step in the operation is the assembling of the biscuits in the baskets.

Assembly of biscuits in the baskets

The shaft 6, see Figures 1 and 3, has three cams 68 fixed to it, and each of these cams cooperates with rollers 69 on rods 70 guided on the machine frame and adapted to contact the bot-

toms of guide blocks 39. The top separators 31 in the baskets are now in alignment with the table 29. As the pusher 21 moves forwardly, it pushes three biscuits over the table 29 into each basket to rest on the top separator. This operation is repeated, baskets rising step by step until the baskets being filled have received four superimposed rows of biscuits. The arrangement illustrated assembles the biscuits simultaneously in three baskets, it of course being understood that any desired number of baskets may be supplied at the same time with biscuits depending on the range for which the machine is built.

The hydraulic cylinder 51 is operated to advance the link conveyor and three filled baskets 30, at a time, so that the filled baskets will eventually reach the position seen in Figures 2 and 4 for the removal of an assembly of biscuits and separators into transfer boxes 71, see also Figures 8 and 9. Each transfer box has its bottom side and rear wall closed, with its top open and a door 72 is provided to close the front opening of the transfer boxes. This door 72 is pivotally mounted on shafts 73. The doors 72 are opened when the assembled biscuits and separators are moved into the transfer boxes by their ejectors 37 which are actuated by the plunger of an hydraulic cylinder 74, see Figure 4, through a member 75, see Figure 2, properly guided. The transfer boxes are mounted on a carriage 76 movable in channels 77 forming a part of a movable bed and are moved by the plunger of an hydraulic cylinder 78.

The door 72 is controlled by a fluid operated device, see more particularly Figures 8 and 9, comprising a fluid receiving casing 79 having a flapper 80 fixed to the shaft 73 on which the door 72 is mounted, and connected with the door by a wire 81. The casing has fluid supply and discharge lines communicating with the main supply and discharge lines 82.

The article supporting surface of each plunger is a plate 83 connected with an hydraulic plunger 84.

Transfer of articles from transfer boxes to containers

When the transfer boxes 71 are moved to the left of the position seen in Figure 4, spring pressed latches 85 on a slide bar 86 engage pins 87 on the transfer boxes 71. 88 are fixed stops for the latches. The bar 86 slides on rails 89 suitably supported.

The transfer boxes are connected to move in unison and the bar 86 is moved to the left to be out of the way of articles being transferred from the transfer boxes to cartons 90 carried by rotatable carton holders 91.

The channel 77, transfer boxes 71 and cylinder 78 and their adjuncts are raised and lowered by four hydraulic cylinders 92, see also Figure 2.

The carton holders 91 have roller carriages 93 forming part of links 94 which cooperate with sprocket wheels 95 mounted on shafts 96. The rollers travel at times in the lower channels 97 and upper channels 98.

The carton holders are of skeleton construction and have their outer ends closed by bars 99 fixed to rock arms 100, on rods 101 on side bars 102. Springs 103 tend to retain the bars 99 in their open or closed position so that each will support vertical rows of superimposed articles. The rods 101 have contact arms 104 in the path of strips 105 controlled by hydraulic plungers 106 to move the strips 105 to open position or closed position.

The cartons 90 are positioned by angles 107 carried by the bottom of a carton holder and the flaps of the carton are held open by spring clips 108.

The conveyor for the carton holders is advanced by a hydraulic cylinder 109, see Figure 11, which moves a spring pressed arm 110 against an arm 111 carried by a roller carriage 93.

Timing and control mechanism

The main driving shaft 6 has cam operated, program type, time controls of conventional construction, with the cams properly adjusted, and controlling solenoid valves. The shaft 6 has a series of cam controls 112, 113, 114, 115, 116, 117, 118, 119, 120, 121, and 122 controlling respectively solenoid valves 123, 124, 125, 126, 127, 128, 129, 130, 131, 132, and 133, which, in proper sequence, control the different operating cylinders and their plungers.

The solenoid valve 123 controls supply and discharge lines 134 to cylinders 109 and 51. The solenoid valve 124 controls supply and discharge lines 135 to cylinder 74. The solenoid valve 125 controls supply and discharge lines 136 to cylinders 92. The solenoid valve 126 controls supply and discharge lines 137 to cylinder 84. The solenoid valve 127 controls supply and discharge lines 138 to casing 79. The solenoid valve 128 controls supply and discharge lines 139 to cylinder 78. The solenoid valve 129 controls supply and discharge lines 140 to one set of cylinders 106. The solenoid valve 130 controls supply and discharge lines 141 to the other set of cylinders 106. The solenoid valve 131 controls supply and discharge lines 142 to cylinder 82. The solenoid valve 132 controls supply and discharge lines 143 to cylinders 59. The solenoid valve 133 controls supply and discharge lines 144 to suction cups 58.

The operation will now be apparent to those skilled in this art and is as follows:

The first step in the operation is the insertion of separators 31 into the baskets 30. Assuming that the motor 2 is started and sufficient pressure applied to the cylinder 57 to maintain the top separator at the proper height, suction is applied to suction cups 58, so that when hydraulic cylinder 59 is actuated, its plunger will raise the suction cups and thereby three separators into position to register with the separator supporting flanges of the angles of the baskets at separator station A. The cam 64 on shaft 10 is beginning to rise and when at the highest point the separators carried by the suction cups, when the cylinder 62 is operated, will move the separators into the baskets above their spacers 34. The suction on the suction cups 58 is released and the cylinder 62 returns the suction cups and cylinders 59 to the position seen in Figures 2 and 3. The cams 64 next lowers the three baskets one step and the operation is repeated to insert the next row of separators. Then, the baskets are again lowered one step to insert the third row of separators.

The hydraulic cylinder 51 is now actuated to advance the link conveyor 40 to bring other baskets 30 into position to receive separators.

The baskets having separators are intermittently advanced to station B, see Figure 1, in position to receive the biscuits or other articles to be packed. At this time, the baskets 30 to be filled are positioned by the cams 68, see Figure 3, to receive the uppermost row of articles. The shaft 16 driven by sprocket chain 4, sprocket

wheel 5, sprocket wheel 13, sprocket chain 14 and sprocket wheel 15 to reciprocate the pusher 21 by links 18 and arms 17. As the pusher 21 moves forwardly it moves a row of biscuits on the conveyor 11 into the three baskets above the upper separator. The rod 20 raises the latch 28 so that the rod makes its return stroke in the upper stretches of tracks 23 to raise the pusher above biscuits which may be on the conveyor 11 which is feeding a supply of biscuits from the oven. The cams 68 intermittently raise the baskets to be filled and the operation of assembling a unit of biscuits in the baskets 30 is repeated. The filled baskets now drop to their down position and the basket conveyor 40 is advanced to bring the filled baskets 30 into position C, see Figure 2, which is the transfer position for a unit of assembled biscuits.

The transfer boxes 71 are now in the position seen in Figure 4 with their closure 72 in open position. The cylinder 74 is now operated to move forwardly the member 75 and thereby the ejector members 38 to cause the ejectors 37, see also Figure 7, to move the three unit assemblies of biscuits from their baskets into the transfer boxes 71. The cylinder 78 is now actuated to move the transfer boxes rearwardly and during the beginning of such travel fluid is supplied to casing 79 to cause the arm 80 to rock the shaft 73 in a direction to close the doors 72 and retain them in closed position. As the transfer boxes 71 travel rearwardly the hooks or latches 85 engage the pins 87 and the bar 86 is moved rearwardly beyond the carton holders 91. The carton holders have been supplied in any desired manner with cartons and the outer flaps of the cartons are held in open position by the spring clips 108. The bars 99 are now in their open position and are held open by the springs 103. The transfer boxes are now under the inverted cartons. The cylinders 92 are now actuated so that the tops of the transfer boxes come into contact with the inverted cartons. The cylinders 84 are actuated to move the assembly of biscuits into the cartons 90. The cylinder 78 moves the transfer boxes 71 forwardly, the latches 85 being released by the fixed stops 88. The bars 99 are now moved to closed position to hold the biscuits in the cartons when cylinders 92 are next returned to their normal position, lowering the supporting bar.

The cylinder 109 now operates to move the conveyor 94 and the filled cartons are brought into upright position as seen at the upper end of Figure 10. The plunger rods 106 at the upper portion of Figure 10 operate to move the bars 99 into their open position. The filled cartons are then removed and the flaps sealed in any desired or conventional manner.

For the first complete revolution of the basket conveyor, the second basket in line of travel at station A, would not automatically receive separators due to the position it assumes relatively to the separator feeding mechanism, and has the separators manually inserted, but thereafter the assembly of separators and biscuits in their baskets is entirely automatic during the operation of the machine.

Having thus described my invention, what I claim as new and desire to secure by Letters Patent is:

1. In a packing machine, an endless conveyor, baskets mounted on said conveyor to be raised and lowered, means to limit downward movement of a basket; separator mechanism having stacks

of separators and means to feed separators from said stacks into said baskets, means to adjust the position of baskets to cause the separators to be spaced therein, article feeding mechanism to feed rows of articles into said baskets, means to move said baskets to cause the rows of articles to be superimposed with separators between the rows, and means including ejectors movable within the baskets to transfer assembled units of articles and separators in the baskets into cartons.

2. In a packing machine, an endless conveyor, baskets mounted on said conveyor to be raised and lowered, separator mechanism to feed separators into said baskets, means to adjust the position of baskets to cause the separators to be spaced therein, article feeding mechanism to feed rows of articles into said baskets, means to move said baskets to cause the rows of articles to be superimposed with separators between the rows, transfer boxes, means to move units from said baskets into said transfer boxes, and means to move the units from said transfer boxes into inverted cartons.

3. In a packing machine, an endless conveyor, baskets mounted on said conveyor to be raised and lowered, separator mechanism to feed separators into said baskets, means to adjust the position of baskets to cause the separators to be spaced therein, article feeding mechanism to feed rows of articles into said baskets, means to move said baskets to cause the rows of articles to be superimposed with separators between the rows, transfer boxes, means to eject as a unit articles and separators to said transfer boxes, carton holders, means to position the transfer boxes beneath inverted cartons in said carton holders, means to move the units from the transfer boxes into the cartons, and means to feed the carton holders into and from the position to receive the units.

4. In a packing machine, article feeding means, a conveyor movable in proximity to said feeding means, article receiving baskets carried by and raised and lowered relatively to the conveyor, separator means to feed separators into the baskets and having individual separators arranged in stacks, means to move rows of articles being fed into said baskets to thereby form with the separators assembled units, carton feeding means, transfer means including ejectors movable within the baskets to transfer units into the cartons of said carton feeding means, and means to occasion the cyclical operation of said conveyor, baskets, and all of said means.

5. In a packing machine, a conveyor, baskets movably carried thereby and of skeleton formation with the outer end open, spring tensioned ejectors vertically disposed in said baskets and relatively movable therein, means to actuate said conveyor, means to raise and lower said baskets,

means to feed articles into said baskets, and means to actuate said ejectors.

6. In a packing machine, a conveyor, baskets vertically movable on said conveyor, and having superimposed, spaced separator supports, a stack of separators, a rod in alignment with and supporting a basket when the latter is brought by the conveyor into its separator receiving position, cam means to effect the lowering of said rods to effect step by step lowering of said baskets, means to move individual separators from said stack into the baskets to rest on the separator supports, means to raise said baskets step by step at their article receiving positions, means to assemble articles in superimposed relation in a basket with a separator between adjacent rows, and means to move assembled articles and separators as a unit from a basket into a carton.

7. In a packing machine, a conveyor, baskets vertically movable on said conveyor, and having superimposed, spaced separator supports, a stack of separators, a rod in alignment with a basket when the latter is in its separator receiving position, and on which the basket is supported at such time, cam means to lower said rods to effect step by step lowering of a basket, means to move individual separators from said stack into a positioned basket to rest on said separator supports, means to raise said baskets step by step at their article receiving position, means to assemble articles in superimposed relation in a basket with a separator above each article, an ejector in a basket, a transfer box, means to actuate an ejector to move an assembled unit of articles and separators from a basket into a transfer box, and means to move an assembled unit from a transfer box into a carton.

8. In a packing machine, an endless conveyor, baskets carried by said conveyor, means to assemble articles in said baskets with a separator above each article below the uppermost article, transfer boxes, carriages for said transfer boxes, means to move articles and separators from said baskets into said transfer boxes, carton holders, said transfer boxes being movably supported from a lowered to a raised position, and means to raise said transfer boxes to transfer the articles and separators into cartons.

9. In a packing machine, an endless conveyor, baskets carried by said conveyor, means to assemble articles in said baskets with separators above all of the articles below the uppermost article, transfer boxes, carriages for moving said boxes, means to move articles and separators from said baskets into said transfer boxes, carton holders, an endless conveyor to revolve the carton holders and means to move the transfer boxes to transfer assembled articles and separators into cartons which have been brought into inverted position by said carton holders.

HERMAN L. DIEHL.
